(57) **CLAIM**

The ornamental design for a crib, as shown and described.

DESCRIPTION

FIG. 1 is a front top left perspective view of the crib showing our new design.

FIG. 2 is a front top right perspective view thereof.

FIG. 3 is a front view thereof.

FIG. 4 is a right side view thereof.

FIG. 5 is a back view thereof.

FIG. 6 is a left side view thereof; and,

FIG. 7 is a top view thereof.

The broken lines shown in FIGS. 1-7 of the drawings represent portions of the crib that form no part of the claimed design.
